United States Patent Office.

WILLIAM L. HORNE, OF BATAVIA, ILLINOIS

Letters Patent No. 65,082, dated May 28, 1867.

IMPROVEMENT IN STEAM WATER-ELEVATORS.

The Schedule referred to in these Letters Patent and making part of the same.

TO ALL WHOM IT MAY CONCERN:

Be it known that I, WILLIAM L. HORNE, of Batavia, in the county of Kane, and State of Illinois, have invented a certain new and improved Water-Elevator; and I do hereby declare that the following is a full, clear, and exact description of the construction and operation of the same, reference being had to the accompanying drawings, and to the letters and marks thereon, which said drawings form part of this specification, and by

Figure 1 give a view by vertical section of a water-elevator constructed under my invention; and, by

Figure 2, a view in elevation of the same.

These drawings show this elevator to have a cylindrical form; but, as is evident, the special form does not constitute an essential part of the invention, as it may have some other than a cylindrical form exteriorly, and the several parts, interiorly, may also be different from what is here shown without departing from or going beyond the scope of my invention.

As represented by the drawings, within an exterior cylinder, *a*, there is an interior cylinder, *b*, and a valve or head, *c*, with an exterior, *d*, below the cylinder, having an outlet guarded by a valve, *e*, such devices or appliances being attached to the valve *e* as will adapt it to and cause it to meet the different conditions and circumstances of the operation of the elevator, with a further extension, *f* *g*, at the bottom of that, *g*, there being an inlet, controlled by a valve, *h*. From the upper portion of the cylinder *a* a pipe, *i*, extends to a valve-chest, *j*, this pipe *i* making the steam communication between the interior of the cylinder *a* and the valve-chest *j*. A valve, *k*, within this chest *j* is attached to a rod, *l*, passing through the top and bottom of the valve-chest, and having suitable stuffing-boxes around it, which rod *l* continues on down through valve or head *c* and through a bar, *m*, affixed to the plate *n* of the cylinder *a*. The rod *l* has tappets or studs *o* *p* and *q* that aid in limiting its motions and in controlling the valves. The valve or head *c* surrounds and moves on the rod *l*. The cylinder *b* has a movement from the bottom to near the top of the cylinder *a*, the upper and lower surfaces of cylinder *b* being bevelled, as shown, and of the character of a valve, the seat for the lower beveling being at *r*, and the upper beveling, at certain times, resting against the lower face of the valve or head *c*. The part indicated by the blue lines or marks between the cylinder *a* and the cylinder *b* will be occupied by oil, forming packing, and lubricating the surfaces thereabout, the oil rising and lowering with the cylinder *b*, and thus being between the surfaces of the two cylinders at whatever point of elevation or depression the cylinder *b* may be. The rods *s*, attached to the bar *m*, limit the downward motion of the valve or head *c*. Supposing the interior of this elevator filled with water, the valve or head *c* and the cylinder *b* would, by their buoyancy, be near the top of the cylinder *a*, the outlet-valve *e* being closed and the inlet-valve *h* being open. The valve *k*, controlling the admission of the steam, having been properly adjusted on its stem to meet the condition and position of the parts as here recited, would be off from its seat and admitting steam into the pipe *i*, which steam would press upon the valve or head *c* and the upper edge of the cylinder *b*, or upon so much thereof as was exposed, forcing the head and cylinder and water downwards, closing the inlet-valve *h* and opening the outlet-valve *e*, the water passing out to a chute or to such place as was desired. Under the pressure of the steam the head *c* and cylinder *b* will be carried down together until the head *c* comes in contact with the rods *s*, which rods will prevent the further descent of the head *c*, and the steam then will act upon the cylinder *b* and directly upon the surface of the water. The water, being discharged, the steam will be condensed, and a vacuum then existing the outlet-valve *e* will be closed and the inlet-valve *h* opened, the water coming in, filling the cylinder, elevating the cylinder *b* and valve or head *c*, and, by the coming of the head *c* against the tappet *o*, operating the valve *k*, and thus putting the parts in the condition first herein recited for the discharge of the water. A low degree of pressure, even as low as one pound, may be used if the elevator be properly constructed. Any higher degree of pressure of the steam may also be used; so that elevators constructed under my invention may be made and adapted to the raising and elevating of water and other fluids to meet any condition and circumstances.

What I claim as my invention, and desire to secure by Letters Patent, is—

A water-elevator, consisting of the exterior cylinder *a*, and the interior valve-cylinder *b* and valve *c*, operated in the one direction by steam and in the other direction by water, combined and arranged as set forth.

This specification signed this 31st day of July, 1866.

W. L. HORNE.
